UNITED STATES PATENT OFFICE

2,497,318

PARTITION STRIP ASSEMBLING MACHINE

John E. McLaughlin, Julius E. Wilske, and Francis A. McCormick, Alton, Ill., assignors to Owens-Illinois Glass Company, a corporation of Ohio

Application June 7, 1944, Serial No. 539,066

21 Claims. (Cl. 93—37)

1

Our invention relates to machines for assembling strips of cardboard, paper or the like to form partitions such as are commonly used for providing individual cells or compartments in cartons and other containers. The invention is herein illustrated and described as embodied in a machine of the type disclosed in our Patent No. 2,353,842 granted July 18, 1944, for Machines for assembling partitions.

An object of the present invention is to provide a simplified and improved mechanism for controlling the operations of the partition strip assembling motor.

Other objects of the invention will appear hereinafter.

Referring to the accompanying drawings:

Fig. 1 is a side elevation of the machine.

Fig. 2 is a diagrammatic view, with parts shown in section, of the air system including the air-operated piston motor for assembling the partition strips and the valve mechanism controlling the operations of the motor.

Figs. 3 and 4 are part-sectional diagrammatic views of the trip valve mechanism shown in Fig. 2 but with the parts in different relative positions.

Fig. 5 is a fragmentary part-sectional plan view showing strip guiding means and the trip valve mechanism.

Fig. 6 is a part-sectional side elevation of parts shown in Fig. 5.

Fig. 7 is a front elevation of the trip valve mechanism.

Fig. 8 is a section at the line 8—8 on Fig. 6.

Referring to Fig. 1, the operating parts, which are mounted on a framework 10, include an electric motor 11 which operates continuously through speed reduction gearing including belts 12 and 13 to drive an endless belt conveyor 14. The conveyor carries longitudinal partition strips 15 forwardly in a horizontal direction to and through an assembly zone in which they are assembled with cross partition strips 16. Cross bars 17 are attached to the conveyor 14 at intervals therealong for engaging the strips 15 and holding them properly spaced lengthwise on the conveyor. Stationary guide bars 18 extending lengthwise of the conveyor, serve to support the strips 15 in upright position and suitably spaced laterally. The strips 15 are provided with vertical slots 20 to receive the cross partition strips 16, the lower ends 21 of the slots serving as stops for the cross partitions which are likewise provided with corresponding slots to receive the lower halves of the longitudinal strips.

The stack of cross strips 16 is supported on an

2

inclined frame member 22 and fed forward by a pusher bar 23 which is slidably mounted on the frame member 22. A weight 24 is connected through a cord 25 and system of pulleys to the bar 23 for applying a yielding pressure of the bar against the stack of strips 16. The cross partition strips are assembled with the longitudinal strips by a piston motor 26. The parts thus far described are the same as illustrated and described in the patent above mentioned to which reference may be had for a more complete disclosure of the general construction and operation of the machine.

Referring now to Fig. 2, the piston motor 26 is operated by air under pressure or other fluid. The air control system includes a main air supply pipe 27 which supplies air under pressure through a valve 28 and filter 29 to an air pressure tank 30. A pressure line 31 extends from the tank to a master control valve 32 which controls the operation of the motor 26. This valve includes a stem 33 movable lengthwise in the valve casing 34. The pressure line 31 is connected to the valve at a central port 35. Pipes 36 and 37 extend from the valve 32 to the upper and lower ends respectively, of the motor cylinder. The valve stem 33 is operated by puffs of air which are supplied alternately through the opposite ends of the valve cylinder. A multiple valve unit 38, herein referred to as the trip valve, is actuated by the partition strips as hereinafter described, and controls the supply of air for operating the master valve stem 33 in one direction, the latter being operated in the other direction by air under pressure controlled by a poppet valve 39.

The trip valve 38 comprises three valve stems or pistons designated 1, 2, and 3, respectively, said stems being mounted for reciprocation in the valve casing 40. A pressure pipe 41 connected to the pipe 31 at a junction 42, (Fig. 2) extends to the left-hand end of the valve casing 40. The pressure line is extended through the valve casing, connecting the valve chambers in series, and thence through a pipe 43 to the master control valve 32. The valve stems 1, 2, and 3 are moved in one direction by coil compression springs 44 and in the opposite direction by the longitudinal strips 15 operating through pivoted dogs 1^a, 2^a, and 3^a, respectively.

The guide bars 18 (Fig. 5) are arranged in pairs, the bars of each pair being spaced apart a distance somewhat greater than the thickness of the strips 15, permitting free forward movement of the strips. The space is narrowed down at the forward end of the bars 18 by a spacing block 45

attached by screws 46 to a plate 47 which is in turn secured to one of the guide bars 18. The block 45 has an inclined surface 49 to guide the strips 15 into position between the spacing block and the opposite guide bar 18.

The trip valve 38 is adjustably mounted at the forward end of one of the guide bars 18, directly opposite the guide block 45 on the other guide bar of the pair. The valve is adjustable lengthwise of the guide bars, being connected by a pivot 10 pin 50 to a slide plate 51 mounted for lengthwise movement in guideways provided by a guide frame 53 attached to the guide bar 18. The valve is adjusted by means of an adjusting screw rod 54 threaded through a lug 55 on the slide plate 51, the screw rod being journalled in the frame 53 and provided with an adjusting knob 56. The valve casing 40 is yieldingly held in operative position by means of a coil compression spring 57 mounted on a rod 58, one end of which is connected by a pivot 59 to the valve casing and in other end of which is slidable in the lug 55.

As shown in Figs. 6, 7, and 8, the valve stem 2 and the dog 2^a operated thereby are mounted at a level above the path of the lower ends 21 of the slots 20 and the dog 2^a is formed with a nose 60 adapted to be projected into each of the slots 20 in succession as the strip 15 advances. The valve stems 1 and 3 are located below the path of the slots 20.

Referring to Figs. 2, 3, and 4, it will be noted that as the valve chambers are all connected in series in the pressure line, all of the valve stems or pistons must be in open position to admit pressure to the master valve. This open position is shown in Fig. 2 in which the dog 2^a is in its projected position while dogs 1^a and 3^a are held in their retracted position by the partition strip 15, thereby holding the valve stems 1 and 3 in their open position. The middle valve is open when the stem 2 is projected, this being permitted when the nose 60 of the dog 2^a enters a slot 20. In Fig. 3 the partition strip 15 is shown advanced to a position in which all of the dogs are retracted so that the pressure line is closed by the valve stem 2. Fig. 4 shows the valves in their projected position assumed when there is no partition strip 15 opposite any of the dogs so that the stems 1 and 3 are in closed position.

The operation of the partition assembling mechanism will now be described, having reference particularly to Fig. 2. With the parts in the position here shown, the stem 33 of the master valve 32 has just been moved to the right so that air pressure is being admitted from the tank 30 through pressure line 31, the master valve, and pipe 36 to the upper end of the motor cylinder. The motor piston 61 and piston rod 62 are therefore moved downward, thus imparting a downward stroke to the partition assembling plate 63 attached to the piston rod. The plate 63 is herein referred to as the pusher plate. As it moves downward it drives across a cross partition strip 16 down and thereby assembles it with a group of the longitudinal strips 15, all as fully set forth in the above mentioned patent.

As the strips 15 are advancing continuously, the valve 2 is only opened momentarily while the slot 20 is moving past the nose of the dog 2^a. The dog is then swung inward to the Figure 3 position, thereby closing the valve 2 and cutting off the pressure to the master valve, and permitting the pressure at the left-hand end of the valve stem to be dissipated through the vent 64. As the pusher plate 63 nears its lowered position,

a cam 65 carried thereby, momentarily opens the poppet valve 39. This admits pressure from the tank 30 through the line 31, junction 42, pipe line 56, poppet valve 39 and line 67 to the right-hand end of the master valve 32, so that the valve stem is moved to the left, thus reversing the connections for the piston motor so that the piston moves upward and lifts the pusher plate. As the forward movement of the partition strips brings the slots 20 in succession to a position in register with the dog 2^a, the operation is repeated for each slot. In this manner, the required number of cross strips 16 are assembled with a group of the longitudinal strips. The pressure line then remains closed through the trip valve unit until the next group of strips 15 is brought to the assembly position.

After the assembling operations for a group of strips is completed, the strip 15 which controls the trip valves during such operations, passes beyond valve 1 so that the latter is moved to closed position (Fig. 4) and the pressure line is held closed. When the strip 15 passes beyond the dog 3^a, the valve 3 is also closed, thus holding the pressure line closed independently of the valves 1 and 2. The next succeeding strip 15 is advanced to a position to hold all of the dogs back before the first slot 20 therein releases the dog 2^a and starts the assembly operation of the next group.

Modifications may be resorted to within the spirit and scope of our invention.

We claim:

1. Apparatus for assembling partition strips, comprising means for feeding strips to an assembly station, means for guiding a said strip in a predetermined path during its movement to the assembly station, an air-operated motor, means actuated by said motor for assembling said strips with other strips at said station, a master control valve controlling the operations of said motor, trip valve mechanism including a plurality of trip valves, an air pressure line extending to said master control valve, said trip valves having valve chambers connected in series in said pressure line, and dogs individual to said trip valves and mounted in position to actuate said trip valves, said dogs extending into said path in position to be actuated in a predetermined order by the said partition strip.

2. Apparatus for assembling partition strips, comprising means for feeding strips to an assembly station, means for guiding a said strip in a predetermined path during its movement to the assembly station, an air-operated motor, means actuated by said motor for assembling said strips with other strips at said station, a master control valve controlling the operations of said motor, an air pressure line extending to the master control valve, trip valve mechanism including a plurality of trip valves in said line and positioned adjacent to the path of a said partition strip, dogs individual to said trip valves and in position to operate the valves, and each positioned to project into said predetermined path of a said partition strip and to be actuated thereby.

3. Apparatus for assembling partition strips comprising means for supporting a group of longitudinal strips on edge, said strips having vertical slots at intervals therealong extending from one edge to an intermediate position, means for supporting a group of cross strips, means for advancing the longitudinal strips to an assembly station, means for guiding a said longitudinal strip in a predetermined path as it advances,

means for assembling the cross strips singly and in succession with the group of longitudinal strips, said assembling means comprising an air-operated motor, a master control valve controlling the operations of said motor, trip valve mechanism controlling the master control valve, said trip valve mechanism including trip valves positioned adjacent to the said predetermined path, dogs individual to said valves and interposed between the valves and said path and projecting into said path in position to be operated by said strip, one of said dogs having a nose in the path of said slots, permitting the release of the dog from the control of said strip.

4. Apparatus for assembling partition strips comprising means for supporting a group of longitudinal strips on edge, said strips having vertical slots at intervals therealong extending from one edge to an intermediate position, means for supporting a group of cross strips, means for advancing the longitudinal strips to an assembly station, means for assembling the cross strips singly and in succession with the group of longitudinal strips, said assembling means comprising an air-operated motor, a master control valve controlling the operations of said motor, an air pressure line extending to said master valve, trip valve mechanism including valves in said pressure line positioned adjacent to and one in advance of another along the path of a said longitudinal strip, springs for moving said valves toward the strip, and dogs individual to said valves and interposed between said valves and the path of said longitudinal strip and arranged to be actuated in succession by the strip and thereby move the valves in opposition to said springs.

5. Apparatus for assembling partition strips comprising means for supporting a group of longitudinal strips on edge, said strips having vertical slots at intervals therealong extending from one edge to an intermediate position, means for supporting a group of cross strips, means for advancing the longitudinal strips to an assembly station, means for assembling the cross strips singly and in succession with the group of longitudinal strips, said assembling means comprising an air-operated motor, a master control valve controlling the operations of said motor, an air pressure line extending to said master valve, trip valve mechanism including valves in said pressure line positioned adjacent to and one in advance of another along the path of a said longitudinal strip, springs for moving said valves toward the strip, and dogs individual to said valves and interposed between said valves and the path of said longitudinal strip and arranged to be actuated in succession by the strip and thereby move the valves in opposition to said springs, one said valve being movable to closed position by its said dog and another said valve being movable to open position by its said dog.

6. Apparatus for assembling partition strips comprising means for supporting a group of longitudinal strips on edge, said strips having vertical slots at intervals therealong extending from one edge to an intermediate position, means for supporting a group of cross strips, means for advancing the longitudinal strips to an assembly station, means for assembling the cross strips singly and in succession with the group of longitudinal strips, said assembling means comprising an air-operated motor, a master control valve controlling the operations of said motor, air pressure lines extending to the master valve, the latter being reversible by air pressure supplied

5 alternately through said lines, trip valve mechanism comprising trip valves, valve chambers for the trip valves connected in series in one said air pressure line, dogs individual to the trip valves and interposed between said trip valves and the path of said partition strip and extending into said path, the dogs being arranged to be operated singly and in succession by said strip and to operate said trip valves and cause an operation of 10 the motor piston in one direction, a valve in the other said pressure line, and means operated by the motor for actuating said last mentioned valve and thereby reversing the master valve.

7. Apparatus for assembling partition strips comprising means for advancing a partition strip in a predetermined path, an air-operated motor, means actuated thereby for assembling said strip with other strips, trip valve mechanism including trip valves positioned adjacent the path of said strip and movable toward and from said strip, dogs individual to said valves and interposed between the valves and a strip moving in said path, each said dog being positioned and arranged to be operated in one direction by its valve and in the reverse direction by said strip, and means controlled by said valves for controlling the operation of said motor.

8. Apparatus for assembling partition strips, comprising an air-operated motor, means for advancing partition strips to an assembly station, each strip having slots at intervals therealong, means operated by said motor for assembling strips at said station, trip valve mechanism controlling the operation of said motor, said valve mechanism including a trip valve positioned adjacent to the path of a said strip, spring means for moving the valve toward a strip in said path, a dog interposed between the valve and said strip and held by said strip in position to retract the valve, said dog having a nose in the path of the strip in position to enter said slots in succession as the strip advances and thereby cause the said valve to be reciprocated by the dog and said spring.

45 9. Apparatus for assembling partition strips, comprising an air-operated motor, means for advancing partition strips to an assembly station, each strip having slots at intervals therealong, means operated by said motor for assembling strips at said station, means including trip valve mechanism controlling the operation of said motor, said trip valve mechanism comprising trip valves positioned adjacent to the path of said strip with the valves one in advance of the other, springs for moving the valves toward a strip in said path, dogs interposed between the valves and said strip in position to be operated by the strip and thereby move said valves away from said strip, one said dog having a projection 50 engaging the said strip and adapted to enter the said slots in said strip in succession as the latter advances.

10. Apparatus for assembling partition strips, comprising an air-operated motor, means for advancing partition strips to an assembly station, each strip having slots at intervals therealong, means operated by said motor for assembling strips at said station, a master valve controlling the operation of said motor, an air pressure line extending to said master valve, trip valve mechanism including trip valve chambers connected in series in said pressure line and trip valves in said chambers and positioned adjacent to and spaced along the path of a said strip, said trip valves including end valves and

an intermediate valve, springs for moving said valves toward the path of said strip, said end valves being movable to closed position by the springs, said intermediate valve being movable to open position by its spring, dogs individual to said valves and interposed between the path of the strip and the valves and operable by the strip as it advances to move the valves in opposition to the springs, the dog individual to said intermediate valve being shaped to be released by the slots in said strip and thereby permit the intermediate valve to be opened intermittently as the strip advances.

11. The combination of means for advancing a strip in a predetermined path, means providing an air pressure line, trip valve mechanism including a plurality of trip valves arranged in series in said line and each mounted for movement into and out of position for closing said line, the valves being positioned adjacent to said path, dogs individual to said valves and positioned to operate the valves, each dog being in position to project into the path of said strip and to be actuated thereby.

12. The combination of a valve actuating element, means for moving said element in a predetermined path, an air pressure line, trip valve mechanism including valves in said line and positioned adjacent to said path, springs for moving the valves toward said path, and dogs interposed between said valves and said path and positioned and arranged to be actuated singly and in succession by a single movement of said element and thereby move the valves in opposition to said springs.

13. The combination of a valve actuating element, means for moving said element in a predetermined path, an air pressure line, trip valve mechanism including valves in said line and positioned adjacent to said path, springs for moving the valves toward said path, and dogs interposed between said valves and said path and positioned and arranged to be actuated singly and in succession by a single movement of said element and thereby move the valves in opposition to said springs, one said valve being movable to closed position by its said dog and another said valve being movable to open position by its said dog.

14. In an apparatus for assembling slotted partition strips, the combination of means for moving the said strips in a predetermined path, valve mechanism including a trip valve positioned adjacent to said path, spring means for moving the valve toward said path, a dog having a stationary mounting and interposed between the valve and a said strip in said path and held by said strip in position to retract the valve, said dog having a nose in the path of the strip in position to engage slots in the strip in succession as the strip advances and thereby cause the valve to be reciprocated by the dog and said spring means.

15. In an apparatus for assembling partition strips, one said strip having slots at intervals therealong, means for advancing the strip in a predetermined path, trip valve mechanism comprising trip valves positioned adjacent to the said path with the valves one in advance of another, springs for moving the valves toward the strip in said path, dogs interposed between the valves and said strip in position to be operated by the strip and thereby move said valves away from said strip, one dog having a projection engaging the said strip and adapted to enter

the said slots in succession as the strip advances.

16. In an apparatus for assembling partition strips including a strip formed with slots and movable in a predetermined path, the combination of an air pressure line, trip valve mechanism comprising valve chambers and trip valves therein, said chambers being connected in series in said pressure line with the valves positioned adjacent to and spaced along the said path, said trip valves including end valves and an intermediate valve, springs for moving said valves toward the said path, said end valves being movable to closed position by the springs, said intermediate valve being movable to open position by its spring, dogs individual to said valves and interposed between said path and the valves and operable by the said slotted strip as it advances along said path to move the valves in opposition to the springs, the dog individual to said intermediate valve being shaped to be released by the said slots and thereby permit the intermediate valve to be opened intermittently as the strip advances.

17. A valve assembly including a valve casing provided with a plurality of valve chambers one in advance of another, an air line extending through said valve casing with said chambers arranged in series therein, valves individual to said chambers and mounted for lengthwise movement in said chambers to and from closed positions, springs individual to the valves, one said spring being arranged to normally hold its valve closed and another said spring being arranged to hold its valve open, dogs individual to said valves, and automatic means for actuating the dogs in succession.

18. A valve assembly including a valve casing provided with a plurality of valve chambers one in advance of another, an air line extending through said valve casing with said chambers arranged in series therein, valves individual to said chambers and mounted for lengthwise movement in said chambers to and from closed positions, springs individual to the valves, including a spring arranged to normally hold its valve closed and another spring arranged to normally hold its valve open, dogs individual to said valves, a dog actuating element, automatic means for advancing said actuating element in a predetermined path, said dogs extending into said path, and said element being operable as it advances to actuate the dogs in succession.

19. In an apparatus for assembling partition strips including a strip formed with parallel slots at intervals therealong, means for advancing and guiding said strip in a predetermined path, a valve assembly including a plurality of valves positioned one in advance of another adjacent to said path each valve being movable toward and from said path, valve chambers in which the valves are mounted, an air line in which the valve chambers are connected in series, springs individual to the valves and arranged to project the valves toward said path, said valves including an intermediate valve normally held open by its spring and valves on opposite sides thereof normally held closed by their said springs, said dogs being projected into the path of said slotted strip and operated thereby, said intermediate valve having a nose projecting into the path of said slots for releasing the dog and causing said intermediate valve to open.

20. The combination of means for moving a flat workpiece of sheet material in a direction parallel with the plane of said sheet, means for sup-

porting and guiding the workpiece in a predetermined path during said movement, a fluid operated motor, a motor control valve controlling the operation of the motor, a fluid pressure line extending to the valve, a plurality of trip valves comprising valve chambers connected in series in said line, means for normally closing and holding one trip valve closed, means for normally holding the other trip valve open, and valve actuating devices individual to said trip valves and extending into the said path of the workpiece, the actuating device for the normally closed valve being operable by the workpiece to open its valve, the actuating device for the normally open trip valve being operable by the workpiece to close the valve, said valve actuating devices being mounted and positioned to be engaged by the workpiece at positions spaced apart in a direction transverse to the direction of movement of the workpiece.

21. The combination of means for moving a flat workpiece of sheet material in a direction parallel with the plane of said sheet, means for supporting and guiding the workpiece in a predetermined path during said movement, a fluid operated motor, a motor control valve controlling the operation of the motor, a fluid pressure line extending to the valve, a plurality of trip valves comprising valve chambers connected in series in said line, means for normally closing and holding

one trip valve closed, means for normally holding the other trip valve open, and valve actuating devices individual to said trip valves and extending into the said path of the workpiece, the actuating device for the normally closed valve being operable by the workpiece to open its valve, the actuating device for the normally open trip valve being operable by the workpiece to close the valve, said valve actuating devices being mounted and positioned to be engaged by the workpiece at positions spaced apart in a direction transverse to the direction of movement of the workpiece.
